UNITED STATES PATENT OFFICE.

CHARLES H. WEISGERBER, OF PHILADELPHIA, PENNSYLVANIA.

DESIGN FOR A SPOON.

Application filed March 31, 1925. Serial No. 12,960. Term of patent 14 years.

To all whom it may concern:

Be it known that I, CHARLES H. WEISGERBER, a citizen of the United States, residing in the city and county of Philadelphia, State of Pennsylvania, at Betsy Ross House, 239 Arch Street, in said Philadelphia, have invented a new, original, and ornamental Design for Spoons, of which the following is a specification, reference being had to the accompanying drawing, which forms a part thereof.

Fig. 1 is a face view of the spoon showing my design.

Fig. 2 is a rear view thereof.

I claim—

The ornamental design for a spoon, as shown.

In testimony of which invention, I have hereunto set my hand, at Philadelphia, Pennsylvania, on this 20th day of March, A. D. 1925.

CHARLES H. WEISGERBER.
